(57) **CLAIM**

I claim the ornamental design for a shaft grip combination for a putter, as shown and described.

DESCRIPTION

FIG. 1 is a perspective view of a shaft grip combination for a putter, the broken away section shown for ease of illustration; FIG. 2 is a reduced front elevational view of FIG. 1;

FIG. 3 is another reduced front elevational view of FIG. 1;

FIG. 4 is a side elevational view of FIG. 1;

FIG. 5 is a top plan view of FIG. 1; and,

FIG. 6 is a bottom plan view of FIG. 1.

The broken line showing is included for the purpose of illustration and forms no part of the claimed design.
